UNITED STATES PATENT OFFICE.

ALTIS S. HOPKINS, OF NEODESHA, KANSAS, ASSIGNOR TO THE STANDARD OIL COMPANY, OF NEODESHA, KANSAS, A CORPORATION OF KANSAS.

PROCESS OF DISTILLING PETROLEUM

1,199,463.

Specification of Letters Patent. Patented Sept. 26, 1916.

Application filed December 18, 1915. Serial No. 67,602.

To all whom it may concern:

Be it known that I, ALTIS S. HOPKINS, a citizen of the United States, residing at Neodesha, in the county of Wilson and State 5 of Kansas, have invented a new and useful Improvement in Processes of Distilling Petroleum, of which the following is a specification.

My invention relates to the art of dis- 10 tilling mixed liquids.

The invention is especially concerned with the destructive distillation or cracking of relatively heavy or high boiling point hydrocarbon oils to produce therefrom lighter 15 or lower boiling point products, as carried out, for instance, according to the method disclosed in the patent to William M. Burton, No. 1,049,667, of January 17, 1913.

In the practice of the Burton process referred to, a liquid body of relatively heavy hydrocarbon oil, such for instance as fuel oil and gas oil, the lightest substantial fractions of which have a boiling point approximating 500° F. is distilled under a pressure 25 of upward of four atmospheres and a temperature of from 650° F. to 850° F., whereby such chemical changes are effected as to result in the production of a distillate of substantially lower boiling point and largely 30 of the desired light, saturated constituents marketable, after suitable refining, as gasoline. To obtain a maximum yield of the desired distillate in carrying out this Burton process, it is important to make a separation 35 of the vapors leaving the still, immediately condensing and returning to the still for further treatment any fractions of higher boiling point. This separation is sometimes effected by an air condenser in the form of

40 a relatively large upwardly inclining vapor conduit known as a dephlegmator or run-back, which is surmounted by a condenser proper comprising a plurality of exposed pipes so arranged as to drain into the run-back. From the upper end of this last condenser member the vapors which have escaped condensation pass to the water-cooled coils which drain into a receiver for the distillate. The use of this apparatus as above 45 described entails a considerable heat loss, the heat units given up in so condensing the heavier vapor fractions being dissipated to the atmosphere, and moreover I find that changes of atmospheric conditions so modify 50 the operation of these fractionating con-

densers as to make it difficult, if not impracticable, to accurately control the process.

With these considerations in mind I have devised the present process, by which, in brief, the following objects are accomplished: The heat units given up in condensing the heavier fractions are utilized to preheat a fresh supply of stock which is to be fed to the still for treatment therein. The fractionation of the distilled vapors is 60 controlled with the greatest accuracy and independently of weather conditions.

For carrying out my process I prefer to make use of the apparatus illustrated in the accompanying drawings, and which apparatus forms the subject matter of my companion application Serial No. 67,603, filed December 18, 1915.

In the drawings, Figure 1 is a side elevation, partly in section and partly diagrammatic, of my improved apparatus, Fig. 2 is an enlarged broken sectional view of the heat-exchanging condenser of my apparatus, and Fig. 3 is an enlarged section of one side of a modified form of condenser having 70 a thermostatic feed-regulator applied thereto.

Referring to the drawings, the numeral 1 designates the fire-door, 2, the ash-pit door; 3, the fire-box, 4, the ash-pit, and 5, a combustion chamber leading into the flue 6 and stack 7. Surmounting the fire-box and combustion chamber is the horizontal cylindrical still 8, from the upper side of which and inclining upwardly there leads the dephlegmator, run-back, or vapor outlet pipe 9, at the upper end of which is located the reflux condenser 10. From the upper end of this condenser there leads a vapor outlet pipe 11 by which the vapors are carried through 75 a condensing coil 12 mounted in a water bath 13. A drain pipe 14 carries the condensed distillate from the coil 12 into a receiving drum 15 from which it may be drawn from time to time by the valved outlet pipe 16. For controlling the escape of the incondensable gases by which the desired pressure is maintained upon the still, there is provided a valved escape pipe 17 tapped 80 into the upper portion of the receiver 15.

The detailed construction of the fractionating condenser 10 is shown by Fig. 2, from which it will be seen that this member comprises a substantially-cylindrical vertically-arranged casing or shell 18 intermediate the 105 110

length of which there are arranged transverse tube sheets 19 having tubes 20 expanded therein. By this construction the interior of the shell 18 is divided into three compartments, a lower compartment 21, which is in communication directly with the run-back pipe 9, an intermediate compartment 22, which lies between the tube sheets 19, and an upper compartment 23, which 5 communicates with the compartment 21 through the tubes 20 and has tapped thereinto the outlet pipe 11. Near the lower end of the intermediate compartment 22 an oil-supply pipe 24 is tapped into the same, this 10 pipe communicating with the pump or other source of oil under pressure. A hand-controlled valve 25 and an automatic check-valve 26 are preferably arranged in the pipe 24 adjacent to the condenser. Adjacent to 15 the upper end of the compartment 22 a transfer-pipe 27 is tapped thereinto, this pipe leading downwardly and reentering the shell of the condenser at its lower end to communicate with the lower compartment 21. It is desirable that a cut-off valve 28 be 20 located in the length of the pipe 27. As shown in the drawing the bottom of the compartment 21 is slightly below the point of entrance of the run-back 9, and for the purpose of draining out this sump there is 25 provided a valved drain-pipe 29. A thermometer 30 having its operative portion lying within the upper compartment 23 is preferably extended outwardly through a 30 T-joint in the vapor outlet 11. A second thermometer 31 may be placed in any convenient location in the pipe 27.

The operation of my apparatus described above is as follows: The mixed vapors rising 40 from the still 8 pass outwardly through the dephlegmator 9, which, according to ordinary practice will be uninsulated and will, therefore, itself serve to some extent as a fractionating condenser removing the 45 very heavy vapors and returning them to the still. This operation is not necessary when my apparatus is employed, however, it being possible to thoroughly insulate the conduit 9, depending wholly upon the condenser 10 for the desired effect. After 50 passing through the lower vapor compartment 21 of my condenser, the gases traverse the cooling tubes 20, transferring their heat through the walls of the latter to the oil 55 within the compartment 22, the higher-boiling-point fractions being thereby condensed and caused to drain downwardly into the compartment 21 and from the latter through the conduit 9 back to the still to be again 60 subjected to cracking process. The desired fractions, however, pass through the fractionating condenser in the form of a vapor and by the conduit 11 are carried to the main or water-cooled condenser. By the 65 indications of the temperature as shown by

the thermometer 30, the maximum boiling point of the vapors passing this thermometer may be readily observed, and by manipulating the control valve 25, thereby increasing or decreasing the flow of cooling oil 70 into the compartment 22, the quality of the distillate forming vapor may be changed at will; that is, should the thermometer show a temperature indicating the presence of the objectionable higher boiling-point fractions, 75 the flow of cooling oil may be increased thereby lowering the temperature of the liquid surrounding the vapor tubes 20 and consequently reducing the temperature of and increasing the condensation effect upon the vapors therewithin, causing the higher boiling-point fractions to be liquefied and drained back to the still for further treatment therein.

During the process of distillation, and according to the operation just described, the oil within the compartment 22 gradually moves upward, and entering the upper end of the pipe 27 is conveyed by the latter directly into the vapor compartment 21, its 85 temperature at the time of its entry into this compartment ranging from 400° F. to 500° F. as indicated by the thermometer 31. In this latter compartment there prevails a temperature considerably in excess of that given, by which the lower boiling-point fractions of the inflowing oil are converted into vapor, their sudden expansion having a secondary cooling effect on the mixed vapors from the still, thereby lessening the amount 90 of heat to be transmitted through the vapor tubes 20 and increasing the efficiency of the condenser. A considerable percentage of this oil is converted into the desired fractions within the compartment 21 itself, 105 while the remainder mixed with the condensate from the tube 20 drains back through the conduit 9 to the still for further treatment.

By the operation of the apparatus described above I find that the loss of heat is reduced to a minimum, it being possible to thoroughly insulate or jacket both the vapor conduit pipe 9 and the condenser 10 and thereby free the apparatus entirely from 110 the effect of atmosphere changes. By observing the indications of the thermometer 30 and properly regulating the valve 25, as indicated thereby, it is possible to accurately control the boiling point of the distillate reaching the receiver 15, and to 115 counteract the effect of uneven firing under the still 8. The fresh stock fed into the pipe 24 is so thoroughly preheated during its passage through the compartment 22 that 120 upon entering the vapor compartment 21, all of the desired lighter fractions which it may contain are vaporized and there is 125 reason to believe, moreover, that a certain limited amount of cracking takes place 130

within this chamber also. Since all of the oil fed in by the pipe 24 is in effect added to the charge of the still, it will be seen that the capacity of the latter is increased to 5 this extent, and since the quantity of fuel required and the time for completing a run of the still does not increase proportionately, it may be said that by my process the efficiency as well as the capacity of the distilling 10 apparatus is increased.

In Fig. 3 of the drawing I have shown means by which the valve 25 and consequently the inflow of fresh oil through the pipe 24 may be automatically controlled in 15 accordance with changes of temperature in the upper vapor compartment 23. In the construction shown in Fig. 3 there is mounted within this vapor compartment a thermostat 32 of any approved design and arranged to operate electrical contact devices 20 by which the starting, stopping and reversal of an electric motor 33 is controlled. This motor may be caused to actuate the valve 25 as by providing the latter with a worm-wheel 35 for engagement with a worm 34 driven from the motor 33. By this construction the thermostat 32 may be set for a certain pre-determined temperature, this temperature being the vapor temperature at 25 which the maximum quantity and the best quality of distillate is obtained in the receiver 15, and the thermostat will then act through its electrical connection to open the valve 25 and increase the flow of cooling oil 30 when the temperature of the vapors in the compartment 23 tends to exceed the pre-determined maximum, or, by reversal of the motor 33, will close the valve 25 as the 35 temperature of the vapors in the compartment 23 tends to drop below the desired minimum.

While I have described in considerable detail the preferred method of carrying out my improved process, it is to be understood 45 that this description is illustrative only and for the purpose of making my invention more clear, and that I do not regard the invention as limited to this specific method of operation, nor to any of the steps thereof, 50 except in so far as such limitations have been included within the terms of the following claims in which it is my intention to claim all novelty inherent in my invention as broadly as is possible in view of the prior 55 art.

What I claim as new and desire to secure by Letters Patent is:—

1. The process of treating petroleum

hydrocarbons which consists in distilling a liquid body of the said hydrocarbons, leading 60 the mixed vapors of distillation from the still through a vapor line to a reflux fractionating surface condenser, cooling the surfaces of the said condenser by supplying thereto a fresh and unheated stock of petroleum hydrocarbons, whereby the latter becomes heated, mixing such heated fresh stock with the reflux condensate, leading the mixed stream to the still through the vapor line and condensing and separately collect- 65 ing the vapors passing the said condenser.

2. The process of treating petroleum hydrocarbons having a boiling point of upward of 500° F., which consists in distilling a liquid body of the said hydro- 75 carbons under a pressure of upward of 4 atmospheres and a temperature of from 650 to 850° F., leading the mixed vapors of distillation from the still through a vapor line to a reflux fractionating surface condenser 80 in which the still pressure is maintained, cooling the surfaces of the said condenser by supplying thereto a fresh and unheated stock of a similar petroleum hydrocarbon, whereby the latter becomes heated, leading 85 the mixed stream to the still through the vapor line, mixing this heated fresh stock with the reflux condensate, and carrying off and separately condensing and collecting the vapors passing the said condenser. 90

3. The process of treating petroleum hydrocarbons having boiling points of upward of 500° F., which consists in distilling a liquid body of the said hydrocarbons under a pressure of upward of 4 atmospheres and under a temperature of from 650 to 850° F., leading the mixed vapors of distillation from the still through a vapor line to a reflux fractionating surface condenser in free communication with the said still, 95 cooling the surfaces of said condenser by supplying thereto a fresh and unheated stock of the said hydrocarbons, whereby the latter becomes heated, mixing the said heated stock with the reflux condensate, 105 leading the mixed stream to the still through the vapor line carrying off and separately condensing and collecting the vapors passing the said condenser, and regulating the said supply to maintain a constant tem- 110 perature of the said vapors.
